UNITED STATES PATENT OFFICE.

THOMAS W. WEBLEY, OF BIRMINGHAM, ENGLAND.

BULLET.

SPECIFICATION forming part of Letters Patent No. 634,383, dated October 3, 1899.

Application filed May 8, 1899. Serial No. 716,010. (No model.)

To all whom it may concern:

Be it known that I, THOMAS W. WEBLEY, a subject of the Queen of Great Britain, residing at Birmingham, England, have invented 5 certain new and useful Improvements in Bullets, of which the following is a specification.

This invention relates to bullets or projectiles designed to be fired by revolvers and pistols, and has for its object a bullet which 10 when fired at a low velocity of about six hundred to seven hundred feet per second, such as is obtained by ordinary revolvers, will readily expand or head up on striking a body and to an extent check penetration, thus delivering 15 a considerable shock, whereby the stopping power of a low velocity bullet is so increased that it will arrest the progress of a charging man or an animal even if only a non-vital part of the body is struck.

20 My improvement consists in forming the nose or striking end of an elongated soft-metal bullet flat or substantially at right angles to the sides and providing at the said flat end a cup-shaped recess or cavity, the diameter of the mouth of which is nearly equal 25 to that of the body of the bullet, whereby the said bullet is possessed of less penetrative action and greater expansion on striking an object from the fact that after the flat 30 edge surrounding the front recess or cavity has penetrated then the flesh which comes within the cavity acts as a wedge in spreading or opening out the surrounding metal, so that the bullet is headed up or its diameter 35 increased at the penetrating end.

Figure 1 of the accompanying drawings represents a side elevation of a bullet or projectile constructed according to my invention. Fig. 2 is a longitudinal section thereof. Fig. 40 3 is a view of a flat recessed front or striking end, while Fig. 4 is a view of the recessed back end. Fig. 5 is a view showing how the 45 said flat recessed front end of the bullet is expanded or headed up even when fired at a low velocity and by striking only the fleshy part of a body.

The same letters of reference indicate corresponding parts in the several figures of the drawings.

50 The sides *a* of the bullet are cylindrical throughout their length, and the usual grease-grooves *b* are provided at the rear end. The

forward or sinking end *c* of the bullet is made flat to a plane at right angles to the sides and is provided with a recess or cup-shaped cavity *d*, whose inner end is rounded, while the mouth is of a diameter almost equaling that of the body of the bullet itself and is surrounded by a flat annular penetrating edge *e*, toward which the side walls at the 55 forward end slightly converge. The rear end of the bullet is formed with another and similar recess or cavity *f*, which both balances the bullet to secure accurate shooting and also admits of the metal of the said bullet at that end being expanded to take the 60 riflings of the revolver-barrel.

As has already been observed, one of the principal objects I have in view in designing my invention is to provide a bullet specially 70 adapted for pistols and revolvers which will readily expand or spread on impact with a fleshy substance and exercise an increased stopping power when non-vital parts of a body are struck, notwithstanding the comparatively low velocity at which it is discharged. To attain this end, it is essential 75 that the bullet should expand laterally shortly after striking a body, so as to both increase the shock to the recipient and check excessive penetration, such as occurs with the use of ordinary solid projectiles, which make but a small opening and frequently pass right through a body without any stopping effect.

I am aware that bullets with a recess at the 80 tip or summit of a conical or pointed nose or striking end (either alone or in conjunction with a copper tube or hard-metal peg for facilitating expansion) have been heretofore used, such as in the bullets known as "express" bullets; but in these only a small amount of expansion is obtained, even when fired from a rifle at a high velocity of about 85 two thousand feet per second; but they are quite unsuitable for use with revolvers, as 90 they fail altogether to head up or expand when fired at a low velocity, and, further, such bullets have a penetrating cutting edge at the striking end, which aids penetration instead of checking it, whereas by the employment of a flat, cupped, and blunt striking end, as in my improved bullet, penetration 95 is checked by the parts of the flesh which enter the cavity or cup, opening out the soft 100

metal surrounding the cup into a flat or dome-like front of considerably increasing diameter.

Having now fully described my invention, 5 what I desire to claim and secure by Letters Patent is—

A projectile for the purpose described, formed of soft, easily-expanded material, having an annular, flat, penetrating end, and a 10 recess or cavity at its forward end, the side

walls of said cavity being curved and diverging from its inner end outwardly.

In testimony whereof I have hereunto set my hand in presence of two subscribing witnesses:

T. W. WEBLEY.
